UNITED STATES PATENT OFFICE.

JOSEPH F. BENOIT, OF SANFORD, MAINE, ASSIGNOR TO SANFORD MILLS, OF SANFORD, MAINE, A CORPORATION OF MAINE.

PROTECTOR MECHANISM FOR LOOMS.

Application filed February 7, 1923. Serial No. 617,481.

To all whom it may concern:

Be it known that I, JOSEPH F. BENOIT, a citizen of the United States, and resident of Sanford, county of York, State of Maine, have invented an Improvement in Protector Mechanism for Looms, of which the following description, in connection with the accompanying drawing, is a specification, like characters on the drawing representing like

parts.

This invention relates to a protector mechanism for looms and particularly to a protector mechanism for a double-fabric loom having two shuttle boxes at each end of the lay and two shuttles which are thrown simultaneously across the lay.

The type of protector mechanism herein shown is that known type comprising a protector rod carried by the lay and having a dagger extending therefrom and a frog with which the dagger co-operates to stop the loom whenever the shuttle is improperly boxed.

One of the objects of the invention is to provide a protector mechanism of this type which has a single dagger and which is constructed so that the dagger will remain in operative position when either or neither shuttle is improperly boxed but will be thrown into inoperative position when both shuttles are boxed.

The features wherein my invention resides will be more fully hereinafter set forth and then pointed out in the appended claims.

In the drawings wherein I have illustrated a selected embodiment of my invention, Fig. 1 is a fragmentary sectional view of the front part of the loom embodying my invention and showing the lay in elevation;

Fig. 2 is a rear view of the shuttle boxes at one end of the lay;

Fig. 3 is a top plan view of Fig. 2;

Fig. 4 is a section on the line 4—4, Fig. 2 showing the position of the parts when one shuttle only is boxed;

Fig. 5 is a view of Fig. 4 looking toward the right;

Fig. 6 shows the position of the parts when neither shuttle is boxed.

Inasmuch as the present invention relates simply to the protector mechanism I have not deemed it necessary to illustrate a com-

plete loom but have shown at 1 a portion of a loom frame and at 2 a lay which is 55 carried by the usual lay sword 3. The loom herein shown is a loom adapted to weave a double-pile fabric and the lay is provided at each end with two shuttle boxes 4 and 5 situated one above the other and having a 60 fixed relation to each other as usual in double-pile fabric looms.

Each shuttle box is adapted to receive a shuttle 6 and both shuttles are thrown simultaneously across the lay by means of the 65 usual picker stick 7.

The double-pile fabric woven on the loom is indicated at 8 and this is cut into two fabrics by the knife 9 all as usual in double-pile fabrics, the two separate fabrics being 70 wound on the rolls 10.

The lay 2 carries the usual protector rod 11 which has a dagger 12 extending forwardly therefrom that is adapted to co-operate with a frog 13 slidably mounted on the 75 breast beam 14 of the loom, said frog having the shoulder 15 with which the dagger is adapted to engage. Some suitable loom-controlling mechanism is employed which is actuated to stop the loom when the frog 80 13 is moved toward the right Fig. 1 all as usual in protector mechanisms of this type. Such loom-stopping mechanism may be in the form of a knock-off lever which is actuated by the frog and which knocks off the 85 shipper rod, or may be in the form of a switch for controlling an electric motor by which the loom is operated and which is opened by the movement of the frog. The latter construction is that herein shown 90 and this switch is shown as comprising two contact members 16 and 17 which are normally in engagement thereby closing the circuit 18 of the motor 19 that operates the loom.

The contact 16 is shown as carried by the loom frame 1 but insulated therefrom and the contact 17 is carried by but insulated from a movable member 20 which is adapted to move toward the right Fig. 1 thereby 100 separate the contact 17 from the contact 16. This member 20 may be carried on the end of a control lever 21 which is shown as pivoted to the loom frame at 22 so that the switch may be opened by hand. The 105 member 20 is also constructed so that it will

be shifted to separate the contacts 16 and 17 by the movement of the frog 13 to the right.

In protector mechanism of this type the 5 dagger is normally in position to engage the frog as the lay beats up, but it is thrown out of such position by the shuttle entering the box so that if the shuttle is properly boxed the dagger becomes inoperative to 10 actuate the frog.

In my present invention I have provided a novel means whereby the dagger 12 will be thus rendered inoperative only when both 15 shuttles are properly boxed in the boxes 4 and 5 and will remain operative to move the frog when either shuttle is improperly boxed or when both shuttles are improperly boxed.

Each shuttle box is provided with a shuttle binder of some usual construction, said 20 shuttle binders being indicated at 23 and 24. These binders have the usual construction so that when there is no shuttle in the box they are in an inward position, but when the shuttle enters the box it forces them outwardly.

An operative connection between the shuttle binders 23 and 24 and the protector rod 11 is provided by which when either shuttle is boxed the protector rod will be given a 30 partial turn which, however, is insufficient to raise the dagger above the frog, but the combined movements given to the protector rod by the boxing of both shuttles is sufficient for this purpose. Therefore, when 35 only one shuttle is boxed the dagger, while being partially raised, will yet be insufficiently raised to clear the frog so that when the lay beats up it will engage the frog and thereby stop the loom, but if both shuttles 40 are boxed properly then the dagger is given its complete movement sufficient to clear the frog as the lay beats up and the loom continues running.

The mechanism herein illustrated for accomplishing this comprises two bent levers 45 25, 26 independently pivoted to the lay at 27 and 28, said levers being provided with projections 29 adapted to engage the shuttle binders 23, 24. These levers are acted on by springs 30 which maintain them in engagement with the shuttle binders. The lower ends 35 of the levers bear on opposite ends of a differential lever 31 which is centrally pivoted at 32 to the end of an arm 50 33 that is rigid with the protector rod and extends forwardly therefrom. This arm 33 is acted on by a pulling spring 34 which maintains the differential lever 31 in engagement with the lower ends of the levers 25 and 26.

The construction is such that when there is a shuttle in neither box 4, 5 then the 55 springs 30, 34 hold the levers and the protector rod in a position so that the dagger 12 will be in line with the shoulder 15 of

the frog and, therefore, if neither shuttle is boxed the dagger will engage the frog as the loom beats up as shown in Fig. 6 thereby stopping the loom.

If a shuttle 6 is in the box 4 but there is 60 no shuttle in the other box then the lever 25 will be moved into the position shown in Fig. 4 while the lever 26 will remain in its normal position. This movement of the lever 25 will depress one end of the differential lever 13 and since the other end of said lever bears against the lower end of the lever 26 such movement of the differential lever 31 will move the lever bodily downwardly a distance equal to one-half that 70 which the end of the differential lever has been depressed by the actuating lever 25. This will move the arm 33 downwardly one-half the distance which it would be moved if the lever 25 directly engaged said arm 80 and, therefore, the dagger will be partially raised as shown in Fig. 4, such movement of the dagger being, however, insufficient to carry it above the shoulder 15. Therefore, under these conditions the dagger is still in 85 operative position so that when the lay beats up it will engage the frog and stop the loom. The same operation occurs if the shuttle is boxed in the box 5, but not in the box 4, although in this case it would be the lever 26 which would be moved and the opposite end of the differential lever 31 would be carried downwardly as shown in dotted lines 90 Fig. 5.

If both shuttles are properly boxed as 100 shown in Fig. 1 then both levers 25 and 26 are turned and as the ends 35 of both levers move down simultaneously the differential lever 31 will be carried bodily downward without being turned on its pivot 32 and the 105 protector rod, therefore, will have its full movement sufficient to raise the dagger above the frog as shown in Fig. 1. The lever 31, therefore, differentiates between a movement caused by the boxing of one shuttle and that 110 caused by the boxing of both shuttles so that in the former case the dagger will still remain in its operative position while in the latter case it will be moved into its inoperative position.

While I have herein illustrated a selected embodiment of my invention I do not wish to be limited to the constructional features shown.

I claim:

1. In a protector mechanism for double shuttle looms, the combination with a lay having two shuttle boxes, of a protector rod mounted on the lay, a dagger carried by the protector rod, a frog with which the dagger co-operates to stop the loom, means normally holding the dagger in operative position, an arm rigid with the protector rod, a differential lever pivoted intermediate of its ends on said arm, and two inde- 125

pendent levers pivoted to the lay, one lever engaging one shuttle binder and the other lever engaging the other shuttle binder and both levers bearing on the differential lever but 5 on opposite sides of its pivotal point, whereby when one shuttle only is boxed the corresponding lever will operate through the differential lever to raise the dagger partially but insufficiently to clear the frog, 10 while when both shuttles are boxed both levers act through the differential lever to raise the dagger clear of the frog.

2. In a protector mechanism for double-shuttle looms, the combination with a lay 15 having two shuttle boxes at its end, a shuttle binder for each shuttle box, a protector rod mounted on the lay, a dagger carried by the protector rod, a frog with which said dagger co-operates to stop the loom, of two 20 separate levers pivoted to the lay, one lever being actuated by one shuttle binder and the other lever being actuated by the other shuttle binder and operative connections between the levers and the protector rod 25 whereby the protector rod will be turned to place the dagger in inoperative position only when both levers are operated simultaneously.

3. In a protector mechanism for double-shuttle looms, the combination with a lay 30 having two shuttle boxes each having a shuttle binder, of a protector rod mounted on the lay, a dagger carried by said protector rod, a frog with which the dagger co- 35 operates to stop the loom, an arm rigid with the protector rod, a differential lever centrally pivoted on said arm, and two levers pivoted to the lay and bearing on opposite

ends of the differential lever, said levers being actuated by the shuttle binders when 40 the shuttles are boxed.

4. In a protector mechanism for double-shuttle looms, the combination with a lay having two shuttle boxes, a protector rod mounted on the lay, a dagger carried by the 45 protector rod, a frog with which the dagger co-operates to stop the loom, the arm 33 rigid with the protector rod, the differential lever 31 pivotally mounted on said arm and two independent spring-actuated levers 50 25, 26 pivoted to the lay, each bearing at one end against said differential lever and at the other end against one of the shuttle binders.

5. In a protector mechanism for double 55 shuttle looms, the combination with a lay having two shuttle boxes thereon each having a shuttle binder, a protector rod mounted on the lay, a dagger carried by the protector rod, a frog with which the dagger co-operates to stop the loom, an arm rigid with the protector rod, a differential lever pivoted on said arm, and means actuated by each binder when a shuttle is boxed in the corresponding box to turn the protector rod through the differential lever, the movement given to the protector rod by each binder alone being insufficient to clear the dagger from the frog but the movement of the protector rod which is derived 60 65 from both binders acting simultaneously being sufficient for this purpose.

In testimony whereof, I have signed my name to this specification.

JOSEPH F. BENOIT.
